DENTAL WEDGE FOR TOOTH RESTORATIONS

William E. Horn, 4901 Marconi Ave., Carmichael, Calif.

Filed Aug. 31, 1964, Ser. No. 81,532

Term of patent 14 years

(Cl. D24—1)

FIG-1

FIG-3

FIG-2

FIG-4

FIG-5

FIG-6

FIGURE 1 is a top plan view of a dental wedge for tooth restorations showing my new design;

FIGURE 2 is a side elevation of the article of FIGURE 1;

FIGURE 3 is one end elevation of the article of FIGURE 1;

FIGURE 4 is the other end elevation of the article of FIGURE 1;

FIGURE 5 is a bottom plan of the article of FIGURE 1; and

FIGURE 6 is a cross section, the plane of which is indicated by the line 6—6 of FIGURE 2.

I claim:

The ornamental design for a dental wedge for tooth restorations, as shown.
